UNITED STATES PATENT OFFICE.

DANIEL J. MURNANE, OF ST. LOUIS, MISSOURI, ASSIGNOR TO ZOURI DRAWN METALS COMPANY, OF CHICAGO, ILLINOIS, A CORPORATION OF ILLINOIS.

WINDOW STRUCTURE.

1,159,071.

Specification of Letters Patent.

Patented Nov. 2, 1915.

Application filed February 10, 1913. Serial No. 747,398.

To all whom it may concern:

Be it known that I, DANIEL J. MURNANE, a citizen of the United States, residing at St. Louis, Missouri, have invented a certain new and useful Improvement in Window Structures, of which the following is a full, clear, and exact description, such as will enable others skilled in the art to which it appertains to make and use the same.

10 This invention relates to store-fronts and show-window structures of the type in which the outside glass-clamping member consists of a piece of hollow sheet metal molding that is arranged in engagement 15 with the glass and with a forwardly projecting portion of the stationary frame in which the glass is set.

The main object of my present invention is to provide an inexpensive structure of the 20 character referred to which is so designed that the outside glass-clamping member will remain in snug engagement with the glass and with the forwardly projecting portion of the stationary glass-supporting frame and 25 thus insure a tight joint between these parts.

Another object is to provide a structure of the character described that comprises a hollow sheet metal outside glass-clamping member, fastening devices passing through 30 the lower portion of said member at approximately right angles to the plane in which the glass lies, and means for preventing said glass-clamping member from tilting or moving into an angular position with 35 relation to the glass and the stationary frame when said fastening devices are tightened.

Another object is to provide a structure of the character just described in which the 40 means that prevents the glass-clamping member from tilting comprises a portion that reinforces and strengthens the hollow sheet metal outside glass-clamping member.

Other objects and desirable features of 45 my invention will be hereinafter pointed out.

Figure 1 is a perspective view of a window structure embodying my invention; Fig. 2 is a front elevational view partly broken away of the parts shown in Fig. 1; 50 Fig. 3 is a cross sectional view illustrating

a slight modification of my invention; Fig. 4 is a perspective view of a structure embodying my invention which is also provided with an inside glass-clamping member of novel design; Fig. 5 is a front elevational view of the structure illustrated in Fig. 4, partly in vertical section on the line 5—5 of Fig. 4; and Fig. 6 is a cross sectional view taken on the line 6—6 of Fig. 5.

Referring to the drawings which illustrate the preferred form of my invention, A designates a stationary glass-supporting frame, B designates a sheet of glass that is arranged therein, and C designates the outside glass-clamping member which presses the glass inwardly and holds it in engagement with a shoulder or abutment 1 on the frame A. Said frame is provided with a forwardly projecting portion 2 on which the clamping member C bears, and means which preferably consists of screw-threaded fastening devices 3, are provided for securely connecting the clamping member C to the frame A. The outside glass-clamping member C consists of a piece of hollow sheet metal molding of any preferred cross sectional shape, and the fastening devices 3 pass transversely through the lower portion of said molding at approximately right angles to the vertical plane in which the glass lies. The clamping member C herein shown is provided with a flat base portion 4 that bears upon the forwardly projecting portion 2 of the frame A and an inverted channel-shaped portion 5 whose inner leg bears against the front face of the glass, but I wish it to be understood that my invention is not limited to a structure having an outside glass-clamping member of the cross-sectional shape herein shown for the particular design of the clamping member C is immaterial so far as my broad idea is concerned.

It is necessary that the fastening devices 3 pass through the lower portion of the clamping member C so that they will clear the glass, and in view of the fact that said fastening devices pass through the clamping member C at a point below the neutral horizontal axis of said clamping member, there

is a tendency for the clamping member C to cant or assume an angular position with relation to the glass and to the forwardly projecting portion 2 of the frame A when the fastening devices 3 are being tightened and thus prevent the portions 4 and 5 of the member C from bearing evenly upon the frame A and the glass B, respectively. In other words, when the fastening devices 3 are being tightened the heads of same bear upon the front face of the clamping member C and exert such a great inward pulling force on the lower portion of the clamping member C that the base portion 4 of said member tilts upwardly away from the frame A and the upper edge of the portion 5 of said clamping member tilts outwardly away from the glass. This, of course, destroys the tight joint between the clamping member and the glass and the frame, and it also causes the lower edge of the inner leg of the inverted channel-shaped part 5 of the clamping member C to exert undue pressure on the glass and very often results in breaking of the glass. In order to overcome this tendency of the outside clamping member C to cant or move out of snug engagement with the glass and with the forwardly projecting portion 2 of the glass-supporting frame when the fastening devices 3 are tightened, I have provided the clamping member C with means that coöperates with the fastening devices and with the base portion 4 of said clamping member to prevent said base portion from tilting or moving upwardly away from its coöperating surface on the stationary frame A when the fastening devices pull the clamping member C inwardly toward the glass. The means that I prefer to use for this purpose consists of a reinforcing device D arranged inside of the hollow clamping member C and provided with a substantially L-shaped portion whose vertical leg 6 is provided with openings 7, preferably elongated slots as shown in Fig. 2, through which the fastening devices 3 pass, the device D either consisting of one long member or a plurality of short members, spaced apart at intervals throughout the length of the outside clamping member. The L-shaped portion of the device D is arranged in the manner shown in Fig. 1, the horizontally-disposed part lying upon the base flange 4 of the clamping member C and the vertical leg 6 projecting upwardly from the inner end of said base flange. In view of the fact that the fastening devices 3 pass through the vertical leg of the device D said leg coöperates with the fastening devices 3 to effectively prevent the base flange 4 of the clamping member C from tilting upwardly when the fastening devices are tightened, the portion of the leg 6 that lies between the under side of the screws 3 and

the base flange 4 acting as a stop or abutment that securely holds said base flange in proper position. Consequently, when the fastening devices 3 are tightened the clamping member C will be drawn inwardly in a straight line and thus cause the portions 4 and 5 of said member to remain in snug engagement with the frame and with the glass, respectively. 65

The device D is preferably provided with a curved portion 8 that projects upwardly into the inverted channel-shaped part 5 of the clamping member C and thus reinforces and strengthens said portion, thereby making it practicable to form the outside glass-clamping member C from comparatively 75 thin sheet metal.

Instead of arranging a device D inside of the clamping member C, as shown in Fig. 1, the base flange of the member C could be provided at its inner edge with an upwardly 85 projecting tongue or tongues that would strike against the under side of the fastening devices 3 and thus overcome any tendency of the member C to tilt when the fastening devices 3 are tightened, said tongue 90 or tongues either being formed integral with said base flange or formed on a separate part 9 riveted or secured in any other manner to the base flange 4a of the outside glass-clamping member, as shown in Fig. 3. 95

A structure of the character above-described is inexpensive to manufacture, it can be installed quickly and easily, and as it comprises a means that prevents the outside clamping member C from tilting when it is 100 being drawn into engagement with the glass, the liability of breaking the glass by undue pressure of the clamping member is reduced to a minimum, and a tight joint between the clamping member and the glass and between 105 the clamping member and the forwardly projecting portion of the stationary frame A is always insured.

Instead of having the glass bear against an abutment 1 on the stationary glass-supporting frame, as shown in Fig. 1, an inside clamping member E can be arranged between the glass and the abutment 1 on the frame, as shown in Figs. 4, 5 and 6 of the drawings. The inside clamping member E 115 herein shown is of novel design and is so constructed that it coöperates with the glass to form a gutter for collecting the water that drains down the inner face of the glass. As shown in Fig. 4 of the drawings the inside glass-clamping member E comprises a vertically disposed portion 10 arranged in front of the abutment 1 on the frame A and provided at its upper edge with a forwardly projecting flange 11. The flange 11 120 inclines downwardly slightly toward the glass so as to form the bottom of a gutter whose coöperating vertical wall is formed

by the inner face of the glass B. The front edge of the inclined flange 11 is preferably provided with a depending lip 12 which bears against the inside face of the glass, 5 and at intervals the lip 12 is pressed inwardly so as to form drain openings 16 through which the water escapes from said gutter, but I wish it to be understood that it is not essential that the drain openings be 10 formed in this exact manner as they could be formed in various other ways without departing from the spirit of my invention. The member E is preferably formed from sheet metal, and in order to impart the 15 requisite strength and stiffness to same I employ a number of clips 13 that bear against the rear side of the depending flange 12, said clips being arranged in front of the vertically disposed portion 10 of the member 20 E and being connected to the abutment 1 of the frame A by means of fastening devices 14. Each clip 13 is provided at its upper end with a forwardly projecting portion 15 having an upturned flange that bears 25 against the depending lip 12 on the member E, the clips 13 serving as rigid abutments which prevent the lip 12 from yielding when the glass is pressed against same during the operation of setting the glass. 30 The water that drains through the openings 16 in the top gutter previously described is collected by a bottom gutter arranged below the bottom edge of the glass, as shown in Fig. 4, said bottom gutter being preferably 35 formed by the base portion 4^b of the outside clamping member C and an upwardly projecting flange 17 on the inner edge of said base portion. In the form of my invention shown in Fig. 4 the bottom portion 4^b of this 40 lower gutter is provided with drain openings 18 through which the water escapes, and in the form of my invention shown in Fig. 6 drain openings 19 are formed in the front portion of the clamping member C adjacent 45 the base portion 4^b of same so that the water can escape from the bottom gutter, as indicated by the arrows in Fig. 6.

Having thus described my invention, what I claim as new and desire to secure 50 by Letters Patent is:

1. In a structure of the character described, a glass-supporting frame having a portion that projects forwardly beyond the glass, a hollow sheet metal outside glass-clamping member having a base flange that rests on the forwardly projecting portion of said frame, fastening devices passing 55 through the lower portion of said clamping member and arranged at approximately right angles to the glass for securing said clamping member to the frame, and means 60 arranged adjacent the inner end of said base flange between said flange and the fastening devices for preventing said flange

from tilting when the clamping member is 65 being drawn into engagement with the glass.

2. In a structure of the character described, a glass-supporting frame having a portion that projects forwardly beyond the 70 glass, a hollow sheet metal outside glass-clamping member having a base flange that rests on the forwardly projecting portion of said frame, fastening devices passing through the lower portion of said clamping 75 member and arranged at approximately right angles to the glass for securing said clamping member to the frame, and a device resting on said base flange and spaced away from the glass, said device being provided with a portion through which said fastening devices pass so as to prevent the outside clamping member from tilting or assuming an angular position when it is being drawn into engagement with the glass. 80

3. In a structure of the character described, a glass-supporting frame provided with a portion that projects forwardly beyond the glass, a hollow sheet metal outside glass-clamping member having a base flange 90 that rests on the forwardly projecting portion of said frame, a reinforcing and strengthening device arranged inside of said clamping member and provided with a part that bears upon said base flange, and fastening devices passing through the lower portion of said clamping member and through the part of said reinforcing device that bears upon said base flange for drawing the clamping member into snug engagement 95 with the glass. 100

4. In a structure of the character described, a glass-supporting frame provided with a portion that projects forwardly beyond the glass, a hollow sheet metal outside 105 glass-clamping member having a base flange that rests on the forwardly projecting portion of said frame, a reinforcing and strengthening device arranged inside of said clamping member and provided with a part 110 that bears upon said base flange, fastening devices passing through the lower portion of said clamping member and through the part of said reinforcing device that bears upon said base flange for drawing the 115 clamping member into snug engagement with the glass, and means on said reinforcing and strengthening device that acts as a stop or abutment to prevent the glass from coming in contact with said fastening devices. 120

5. In a structure of the character described, a glass-supporting frame having a portion that projects forwardly beyond the glass, a hollow sheet metal outside glass-clamping member having a base flange that rests on the forwardly projecting portion of said frame, a reinforcing and strengthening 125

device arranged inside of said clamping member and having an L-shaped part that bears upon said base flange, and fastening devices passing transversely through the lower portion of said clamping member and through one leg of said L-shaped part for securing said clamping member to the glass-supporting frame.

Copies of this patent may be obtained for five cents each, by addressing the "Commissioner of Patents, Washington, D. C."

In testimony whereof I hereunto affix my signature in the presence of two witnesses, to this sixth day of February 1913.
